UNITED STATES PATENT OFFICE.

BENJAMIN C. SMITH AND AARON T. JACKSON, OF OLATHE, KANSAS.

DESIGN FOR A MOP-RUBBER.

SPECIFICATION forming part of Design No. 20,152, dated September 9, 1890.

Application filed August 2, 1890. Serial No. 360,833. Term of patent 7 years.

To all whom it may concern:

Be it known that we, BENJAMIN C. SMITH and AARON T. JACKSON, citizens of the United States, and residents of Olathe, in the county of Johnson and State of Kansas, have invented a certain new and useful Design for Mop-Rubbers; and we do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of the invention and is a perspective view. Fig. 2 is a front view, and Fig. 3 is a cross-section.

This invention relates to a new and original design for mops; and it consists in the peculiar form and configuration thereof, as hereinafter disclosed.

In the drawings, A' refers to the body portion of the mop, represented as V-shaped in cross-section and having a row of oblong vertical openings *a* ranging its entire length and disposed at short intervals apart. Through these openings the shank portion appears.

The upper or shank portion of the part A of the mop is a narrow longitudinal V-shaped flange *b*, and its lower part is a double bead *b'*, the latter having a longitudinal depression or groove *b''* in its face. The holder or body portion A' of the mop has also an upper narrow longitudinal molding or extension *c*, provided with a series of curved rib-like projections or bars *c'*, as shown.

Having described this invention, what we claim, and desire to secure by Letters Patent, is—

The design for mops herein shown and described, wherein the body portion A' has a row of oblong vertical openings ranging its entire length, and its portion A' has a narrow longitudinal V-shaped flange and a double bead, the face or bottom edge of the latter having a longitudinal groove or depression, as shown.

In testimony whereof we affix our signatures in presence of two witnesses.

BENJAMIN C. SMITH.
AARON T. JACKSON.
